TOILET SEAT END HINGE LEAF

Leslie H. Coggins, Cross St., Meriden, Conn.

Filed May 26, 1959, Ser. No. 56,073

Term of patent 14 years

(Cl. D4—5)

FIG. 1

FIG. 2

FIG. 4

FIG. 3

FIG. 5

FIG. 6

Fig. 1 is a front elevational view of a toilet seat end hinge leaf showing my new design;

Fig. 2 is a right side elevational view thereof;

Fig. 3 is a left side elevational view thereof;

Fig. 4 is a top plan view thereof;

Fig. 5 is a bottom plan view thereof; and

Fig. 6 is a cross-sectional view thereof taken on line 6—6 of Fig. 1.

I claim:

The ornamental design for a toilet seat end hinge leaf, substantially as shown.
